THERMALLY RESPONSIVE DEVICE

John A. Spencer, Newtonville, Mass., assignor to
 General Plate Company, Attleboro, Mass., a
 corporation of Massachusetts

Application November 2, 1933, Serial No. 696,344

1 Claim. (Cl. 297—8)

This invention relates to thermally responsive devices, and with regard to certain more specific features, to such devices which operate upon the principle of an expanding fluid.

5 Among the several objects of the invention may be noted the provision of a thermally responsive device of the class described; more particularly, a device comprising a sealed bulb, capillary tube, and bellows filled with gas, wherein provision is 10 made for a more perfect sealing of the device against leakage of the gas contained therein and wherein the particular materials of construction, and the gas, are chosen to reduce leakage occasioned by corrosion and the like; the provision 15 of a device of the class described which, accordingly retains its precise operating characteristics over a considerably longer period of utility than prior analogous devices; and the provision of a device of the class described which is relatively simple and economical in construction. Other 20 objects will be in part obvious and in part pointed out hereinafter.

The invention accordingly comprises the elements and combinations of elements, features of construction, and arrangements of parts, which 25 will be exemplified in the structures hereinafter described, and the scope of the application of which will be indicated in the following claim.

In the accompanying drawing, in which is illustrated several of various possible embodiments 30 of the invention,

Fig. 1 is an elevation, partially in section, of a device embodying the present invention;

Fig. 2 is a longitudinal cross-section of the bulb shown in Fig. 1;

Figures 3 and 4 are fragmentary views of the bulb of Fig. 2 in the course of its manufacture; and,

Fig. 5 is a cross-section similar to Fig. 2 but illustrating an alternative embodiment of the invention.

Similar reference characters indicate corresponding parts throughout the several views of the drawing.

For several fields of use, a thermally responsive device of the present type has heretofore been found peculiarly adaptable. The customary construction of such a device comprises a flexible bellows chamber, a capillary tube, and a bulb sealed together to form a unit, which is filled 45 with a fluid which preferably undergoes a considerable volume change within the temperature range which it is desired to control.

The bulb of the unit is ordinarily exposed to the temperature of the medium which it is de-

sired to control, and changes in temperature of the bulb result in expansion or contraction of the gas filling the unit, thereby causing coextensive movement of the free end of the bellows. This movement may be used to operate any desired form of device such as electric switches, valves, or the indicating means of a temperature indicating device.

In such a device, it is essential that the bellows, capillary tube, and bulb, as well as all joints 10 therebetween, be absolutely tight so that operation may not be impaired by leakage and consequent reduction in internal pressure.

Such units have readily been made heretofore for the lower ranges of temperature in which 15 metals readily soldered or welded by ordinary methods can be employed in the construction of the bulb. For more severe conditions, such as are encountered when the bulb must be exposed in use to the heat and corrosive action of impinging gas flames, units made by heretofore known methods and from heretofore utilized materials, have been found unsuitable. This is because the metal or joints would either become porous, permitting the gradual escaping of the gas, or would completely melt or burn out at the high temperature or from the effects of the impinging flame, or would decrease in efficiency because of either a physical or chemical combination or absorption of the gas in the material of the 20 bellows at the high temperatures used.

The present invention provides a thermally responsive device of this general type which is ideally adapted for use at such high temperatures without any of the disadvantages heretofore 35 stated, and which furthermore has a low heat capacity in the part of the element exposed to changes of temperature, thus making it unusually quick in its response to temperature changes.

It has been ascertained, as a result of considerable experimental research, that the above disadvantages may be cured if the bulb is constructed of a stainless steel and if the gas employed is argon. With these two materials, there is no deterioration of pressure in the resulting device under the said high temperature conditions, nor does the bulb itself deteriorate or corrode because of the action of the flame thereon. The particular metals of which the capillary tube and bellows are constructed are 40 not of much consequence, since these portions of the device are rarely, if ever, subjected to any high temperatures which bring about the problems that are desired herein to correct.

Referring now more particularly to Fig. 1, nu- 55

- meral 1 indicates a bellows of customary design. The material of which this bellows is constituted may be spring copper, bronze, or any other material found to be suitable. The end 3 of the bellows 1 is closed, and comprises the free end of the device which undergoes movement in operation. The end 5 of the bellows is welded or soldered in a gas-tight manner to a threaded stem 7, by which the bellows 1 is usually mounted and adjusted as to position. Welded or soldered in a gas-tight manner to the other end 9 of stem 7 is one end of the capillary tube 11. The other end of the tube 11 is secured to the bulb 13.
- 15 The bellows 5, stem 7, tube 11, and bulb 13 are all sealed together and filled with gas, under more or less pressure as the occasion demands. The gas most preferably employed, as stated above, is argon.
- 20 The construction of the bulb 13 from stainless steel is somewhat difficult. This is because in the first place, stainless steel is not an easy metal to work, and in the second place, because in the thin sheets here employed (in order to
- 25 get a quick response to the external temperature, it is decidedly advantageous that the walls of the bulb 13 be as thin as practicable), welding or the ordinary soldering of stainless steel is substantially impossible. The present invention
- 30 also includes a method of manufacturing such a bulb or container by which these disadvantages are obviated.

Referring to Figures 2, 3, and 4, it will be seen that the bulb 13 comprises primarily a tubular portion 15, which is preferably a length of relatively thin seamless stainless steel tubing. At each end of the tube 15 is formed an inwardly directed annular groove 17. The ends of the tube 15 are then closed by inserting stainless steel discs 19 and 21 which seat against shoulders provided by the grooves 17. The disc 19 is circular in shape and has no perforations therein. The disc 21 is likewise circular in shape but has a central opening 23 (Fig. 4), to receive the end of the capillary tube 11.

After the discs 19 and 21 have been placed in position against the shoulders 17, the ends of the tube 15 are over-turned or upset or spun as indicated at numeral 25, and as indicated in dotted lines in Fig. 3, thereby loosely retaining the discs 19 and 21 in position.

The end of the capillary tube 11 is next prepared as illustrated in Fig. 4, by welding or wiping a bead 27 of cast iron around it near the end. The end of the tube 11 is then inserted into the opening 23 in such manner that the bead 27 abuts the disc 21.

The assembly is next placed in vertical position with the tube 11 at the upper end, and the various parts at the end of the tube are desirably cleaned and fluxed. The end is next filled in an ordinary manner using a gas welding torch or the like and a cast iron welding rod. The molten cast iron seems to have an affinity for the stainless steel, and flows readily over it and into the joint, making a smooth, gas-tight weld. In the course of the welding, the bead 27 melts and runs in with the rest of the cast iron. The ultimate appearance of the welded end is that indicated at numeral 29 in Fig. 2.

Using cast iron as a welding material, not only is a secure weld effected without tinning difficulties, but also the temperature required is not so great as to burn or melt stainless steel, even though it is present in thin sheets. This use of cast iron as a welding material was determined upon only after a considerable amount of unsuccessful experimentation and constitutes an important feature of this phase of the invention.

The other end of the bulb 13 is then welded shut in the same general manner with cast iron. The weld is accomplished more easily at this end because of the absence of the capillary tube 11.

Fig. 5 illustrates an alternative construction for the bulb 13, in which the length of tubing of the Fig. 2 embodiment is replaced by a drawn cup 31, also of stainless steel which thus has its end 33 already closed. In this case, it is only necessary to make the weld on the end which includes the capillary tube 11.

The gas may be introduced into the bulb and bellows unit in the customary manner which preferably includes an evacuation of the unit prior to its filling with argon.

In view of the above, it will be seen that the several objects of the invention are achieved and other advantageous results attained.

As many changes could be made in carrying out the above constructions and processes without departing from the scope of the invention, it is intended that all matter contained in the above description or shown in the accompanying drawing shall be interpreted as illustrative and not in a limiting sense.

I claim:

A bulb and bellows type thermally responsive device particularly adapted for high temperature control including a bulb formed of stainless steel, the seams of which are welded with cast iron, and wherein the contained fluid comprises argon.

JOHN A. SPENCER.
